UNITED STATES PATENT OFFICE

2,415,762

POSTAGE PRINTER FOR TAPE

Commodore D. Ryan, Los Angeles, and Frank P. Sager, Alhambra, Calif., assignors to Commercial Controls Corporation, a corporation of Delaware

Original application April 29, 1940, Serial No. 332,305. Divided and this application July 29, 1943, Serial No. 496,559

15 Claims. (Cl. 101—228)

1

This invention relates to a tape feeding device for a postage printing machine.

One of the objects of this invention is to provide as an integral part of a mail treating machine, a gummed tape feeding device which may be positioned for operation or retracted to its inoperative position by the actuation of a single lever, and which tape feeding means is provided with suitable control means to prevent misuse which would result in waste or loss of postage.

Another object is to provide a tape feeding device of the above nature which is simple and sturdy in construction and operation and capable of extended rigorous use. Other objects will be in part apparent and in part pointed out herein-after.

The invention accordingly consists in the features of construction, combinations of elements, and arrangements of parts as will be exemplified in the structure to be hereinafter described, and the scope of the application of which will be indicated in the following claims.

This application is a division of the copending application of Frank P. Sager et al., Serial No. 332,305, filed April 29, 1940.

In the drawings wherein we have shown a preferred embodiment of our invention,

Figure 1 is a perspective view of the mail treating machine;

Figure 2 is an enlarged fragmental sectional elevation showing in detail the tape feeding device in its rest position;

Figure 3 is an enlarged fragmental sectional elevation showing the tape feeding device in its retracted inoperative position;

Figure 4 is an enlarged composite view of the upper portion of the tape feeding mechanism, the tape compartment door and the interlocking mechanism therebetween;

Figure 5 is a view similar to Figure 4, with the exception that the tape compartment door is shown open, in which position the interlocking mechanism will be actuated to retract the tape safety fingers to facilitate threading of the tape into the device;

Figure 6 illustrates the upper portion of the tape feeding device and shows the manner in which the interlocking mechanism will operate to lock the machine against operation when the cut end of the tape is out of position;

2

Figure 7 is a fragmentary sectional view taken substantially in the plane of line 7—7 in Figure 6; and,

Figure 8 is a view similar to Figure 6 with the exception that it shows the operation of the interlocking mechanism to lock the machine against operation when an insufficient amount of tape to complete a full stamp remains in the tape feeding device.

10 Similar reference characters refer to similar parts throughout the various views of the drawings.

The preferred embodiment of the mail treating machine illustrated in the drawings is an all purpose machine, that is, a machine readily adjusted to treating all types and classes of mail matter including first, second and third class mail, registered mail and parcel post, and for printing any one of a wide range of postage values, namely from one-half cent to ninety-nine dollars and ninety-nine and one-half cents by steps of one-half cent, for all of the above classes of mail matter and parcel post. The machine provides for treating the above classes of mail matter at high speed and under full control and protection against waste of postage or unauthorized use, and may be easily and conveniently adjusted to seal and stamp or stamp without sealing or sealing without stamping envelopes of various lengths, widths and thicknesses.

20 The following description of the machine and its operation will be generally directed to the use of the machine while printing postage on gummed tape. In general, accordingly, the machine includes the following major elements and instrumentalities which, for convenience, will be identified by the general reference numbers preceding each of the these elements and instrumentalities:

- 40 150—frame structure.
- 151—feeding hopper.
- 152—stripper.
- 153—conveyor feeding system for the mail matter.
- 45 154—envelope flap moistening device.
- 155—power plant and driving mechanism.
- 156—tape feeding device.
- 157—meter.
- 50 158—ink feeding mechanism for the meter.

The tape feed portion 653 (Figure 2) of the tape feeding device 156 includes a frame member 703 provided at its lower portion with an inner bearing 704 and a spaced outer bearing 705 slidably mounted upon the positioning structure connecting rod 674.

To maintain frame 703 (Figure 3) in proper position during all of its movements, the upper end thereof is provided with a transverse pivot pin 706 upon the outboard end of which is fastened a collar 707 having an annular groove 708 which groove receives the guide surface 709 of guide plate 710. The guide plate is mounted upon the front face of one of the main machine brackets (not shown) as by means of suitable screws 711.

The guide plate 710 is shaped as shown most clearly in Figure 3. The guide surface 709 thereof is curved to substantially coincide with the path of travel of the grooved collar 707 during the raising or lowering movement of the tape feeding device to or from its printing position. The guide plate 710 is provided with a horizontally extending guiding surface 712 overhanging in spaced relation the guide surface 709 for guiding the grooved collar when the tape feed portion 653 of the device is shuttled during a tape printing cycle of operation.

A tape guide chute 713 is mounted upon frame member 703 and includes an entrance portion 714 flared as at 715 (Figure 2) to facilitate entrance of tape therein.

The guide chute above its entrance end is provided with reverse curve portion 716 having suitable openings for a manual feed roller mechanism 717 which mechanism is employed when threading tape into the chute.

From the reverse curve portion 716 the chute extends upwardly and is provided with a horizontal portion the chute is open at its top and bottom to straddle the platen roller 327 and the printing plates carried by the printing drum.

The manual feed roller mechanism 717 may include a feed roller 719 journaled upon frame member 703 by bearing pin 720. The feed roller 719 is preferably provided with ratchet like teeth 721 against which one end of a leaf spring 722 acts to prevent reverse rotation of said roller. The opposite end of leaf spring 722 is fastened to the underside of the tape chute in any suitable manner. The ratchet like teeth 721 also act against the gummed surface of the tape to assist in propelling the tape through the chute. A pressure roller 723 is journaled upon the free end of a lever 724 by a bearing pin 725 while lever 724 is pivotally attached to frame member 703 by a pivot pin 726. A tension spring 727 acting between lever 724 and spring pin 728 carried by the frame member 703 acts to yieldingly press the tape against the teeth of feed roller 719.

The feed roller 719 is provided with a forwardly extending knurled sleeve portion (not shown) for manually turning the feed roller when threading tape into the chute.

A tape roll magazine, generally indicated at 730 may include a housing 731 fastened to the intermediate portion of shaft 732. One end of said shaft is securely mounted in one of the main machine brackets in any suitable manner (not shown). The forward end of shaft 732 is provided with an extension 733 pivoted to said shaft by hinge pin 734.

To mount a roll of gummed tape 735 in the magazine, the shaft extension 733 should be moved into axial alignment with the shaft and

thereafter the roll of tape may be slid onto the shaft and into the housing. After the roll of tape has been mounted within the housing, a retaining plate 736 may be positioned on the shaft and the shaft extension 733 swung downwardly into a slot 737 formed in the hub portion 738 of said plate in the manner shown in Figure 2.

The housing 731 is cut away to permit the tape to feed therefrom and a roller 739 is journaled in brackets 740 carried by the housing to guide the tape as it feeds down under a loop forming roller 741. The tape 735 loops around roller 741 and extends up into and through the tape chute 713.

The loop forming roller 741 is journaled upon the forward end of a swing arm 742 which arm at its opposite end is pivotally mounted upon the positioning shaft 661 (Fig. 2).

The loop forming device pulls from the roll a sufficient amount of tape to provide for the printing of a stamp and maintains this loop under proper tension to insure a uniform resistance during the printing of the stamp independent of the amount of tape remaining on the roll.

During the printing of a stamp the tape is rapidly pulled through the tape chute 713 and if the tape was passed directly from the roll to and through the chute it would tend to rupture in its attempt to overcome the inertia of a full heavy roll or if said tape did not rupture, it would tend to spin the roll unwinding more tape than necessary, and as a result the tape would pile up and foul in the magazine or between the magazine and entrance to the chute, thus rendering the operation unreliable.

When a roll of tape becomes used up, a new roll may be easily and quickly mounted in the magazine in the manner previously described and likewise easily and quickly threaded into proper printing position in the tape chute by pulling out from the new roll a sufficient length of tape to place it over roller 739, under the looping roller 741 and into the entrance portion of the chute unit the end of the tape engages the manual feed roller mechanism 717 whereupon the operator may easily feed the tape through the remaining portion of the chute by turning the knurled sleeve 729 of said feed mechanism.

If an excessive length of tape has been unwound from the roll for the purpose of threading the tape into the chute, this excessive tape may be rewound up the roll.

Retaining plate 736 is preferably made of sufficient length to provide a guide for maintaining the tape upon rollers 739 and 741.

The tape feeding mechanism is provided with safety devices to prevent the operation of the machine and thereby the possible wastage of postage unless the tape is correctly positioned within the tape guide chute 713 (Fig. 4) and unless sufficient tape is contained within the chute to more than complete the printing of a stamp.

The first of these two safety devices 911 may include a detecting finger 912 slidably supported upon the rear side rail 914 adjacent the discharge end of the horizontal portion 718 of the tape guide chute 713 by a headed pin 913 which extends through a suitable slot formed in the end portion of this finger.

The tape guide chute adjacent the finger end 915 of the finger is provided with an opening 916 through which the end 915 will project when the tape does not extend past this portion of the chute as shown in Fig. 6. However, when the tape extends beyond this portion of the guide

chute, it covers opening 916 (Fig. 4) thus preventing the end 915 of the finger from entering into said opening. In this way unless the tape is in correct position to start the printing of a stamp, the detecting finger will actuate and through means to be described, will lock the machine against operation.

For this purpose the lower end of detecting finger is connected to a lug 917 formed adjacent the upper end of stop lever 918 as by a pivot pin 919. The stop lever 918 is mounted upon frame member 703 by a pivot pin 920. A compression spring 921 is interposed between frame 703 and stop lever 918. The purpose of spring 921 is to yieldingly urge the detecting finger 912 into the opening 916 formed in the guide chute. When the tape does not extend across the opening 916, spring 921 will move the detecting finger 912 and stop lever 918 to their respective positions as shown in Figure 6. However, when the tape covers the opening, the detecting finger 912 and stop lever 918 will be to their respective positions as shown in Fig. 4. The manner in which stop lever 918 functions to prevent operation of the machine will be described presently.

The second portion 922 of the safety device may include a bellcrank lever 923 pivoted to frame member 703 by means of pivot pin 920 which is the same pivot pin supporting the stop lever 918. The bellcrank lever 923 is provided with an arm 924 having an offset end 925 which cooperates with an anvil block 926 having a groove 927 into which the offset end 925 of the bellcrank lever is yieldingly urged as shown in Fig. 8 by means of a spring similar to spring 921, which spring is directly in back of spring 921 and, therefore, cannot be seen in the drawings and said spring interposed between the frame 703 and the bellcrank lever stop arm 923. The offset end 925 of bellcrank lever 923 will enter the anvil groove 927 when the tape does not extend through this portion of the tape chute 713. For this purpose, at this locality, the top and bottom plates of the guide chute are slotted. The anvil block 926 is positioned sufficiently remote from the discharge end of the tape guide chute 713 to insure a sufficient supply of tape being contained within the guide chute for the printing of at least one complete stamp, and this portion of the safety device will function to lock the machine against operation in those cases where there is an insufficient length of tape remaining in the chute for the printing of one complete stamp. This condition is shown in Fig. 8 wherein the offset end 925 of bellcrank 923 has swung into the anvil groove 927 and its stop arm 923 has swung into locking position. The stop arm 928 of bellcrank lever 923 corresponds to the position of stop lever 918 as shown in Fig. 6.

The mechanism by which these two safety devices function to prevent operation of the machine includes a control lever 929 securely fastened to the forward end of control shaft 930 which shaft is journaled in bearing 931 on frame member 703 (Fig. 4) and has fastened to its rear end a cam lever 832. A torsion spring 933 is mounted upon shaft 930 between the end of bearing 931 and cam lever 932 and acts between these two members to yieldingly maintain stop lever 929 against stop pin 934. As may be observed in Fig. 4, the push rod 864 is provided with a collar 935 keyed thereto by means of pin 936, against the under surface of which the free end of cam lever 932 is positioned to be engaged when the push rod 864 is depressed.

The control lever 929 at its free end is provided with two outwardly projecting spaced lugs, namely a short lug 937 and a longer lug 938 providing an open space 939 therebetween into which space the free ends of stop lever 918 and stop arm 923 are positioned when the tape is properly positioned and contained within the tape guide chute 713 as shown in Figure 4. The positioning of the two safety devices as just described will permit the machine to be placed in operation by means of the manual tripping lever 857 which in the manner described in the above-noted application depresses the push rod 864 for actuating the meter clutch tripping mechanism (not shown).

During the downward movement of push rod 864, collar 935 will engage the free end of cam lever 932, rotating said cam lever in a clockwise direction as viewed in Fig. 4 and through its connection with control lever 929, will likewise rotate this lever in a clockwise direction. This condition is clearly shown in Fig. 4, whereupon the control lever will swing freely past the ends of stop lever 918 and stop arm 923 thus permitting the machine to be placed in operation with the assurance that a full and complete stamp will be printed during the operating cycle of the machine.

The first safety device 911 will function to lock the machine against operation when the tape does not extend across opening 916 to prevent the movement of detector finger 912 therein. This condition is illustrated in Fig. 6 and as the tape is not in position to prevent the entry of detecting finger into opening 916, the compression spring 921 will act to advance the detecting finger and as a result the stop lever 918 will swing until its abutting end overlies the long stop lug 938 of control lever 929. This will prevent rotation of the control lever in a clockwise direction as viewed in this figure and as a result will lock the manual tripping mechanism so that it cannot be actuated to place the meter driving clutch in operation. This condition can be corrected only by advancing the tape until it again covers the detecting finger slot 916, thereby returning stop lever 918 to its normal position as shown in Fig. 4 whereupon the manual tripping mechanism may be operated in the manner described.

The second safety device acts to prevent operation of the machine when an insufficient length of tape remains within the tape guide chute 713. Fig. 8 illustrates the manner in which the second safety device will operate to lock the machine against operation. In this figure, it may be observed that the end of the tape no longer extends across the anvil block groove 927 to prevent the entrance of the offset end 925 of the second safety device bellcrank lever 923 therein, and as a result the bellcrank lever will rotate in a counterclockwise direction as viewed in Fig. 8, thereby swinging the abutting end of its stop arm 928 over the long stop lug 938 of control lever 929 and as a result locking the control lever 929 against rotation. Thus it will be seen that the locking of control lever 929 will prevent the machine from being manually placed in operation unless there is sufficient tape contained within the tape guide chute 713 to more than print a complete stamp.

The front plate 160 of the machine is provided with a relatively large opening 940 (Fig. 4) to permit access to the tape magazine 130 for replenishing the supply of tape therein. The front plate opening 940 is provided with a door 941 hav-

ing hinge brackets 942 hinged to the front plate 160 by means of hinge pins 943 and a hand knob 945 fastened adjacent the upper edge of the door by means of screw 946 extending through the door from the rear side thereof and screw threaded into said knob. A grooved latch bushing 947 is mounted upon screw 946 between the head portion thereof and the rear face of the door. A latch pin 948 is slidably mounted within a suitable bore 949 formed in the frame plate 160. The latch pin is provided with a rounded point for yieldingly engaging the groove formed in the latch bushing 947 and at its opposite end is provided with a head 950 for seating in the bottom of the counter-bored portion of latch pin bore 949 when the door is swung open. A compression spring 951 is provided to act between the head portion of latch pin and screw plug 952 screw threaded into the upper end of the counter-bored portion of the pin bore. This structure provides a spring latch for yieldingly maintaining the door 941 in its closed position. The door is opened to enable a fresh roll of tape to be mounted within the tape magazine in the manner previously described.

To facilitate threading of the new tape into guide chute 713, means are provided for automatically retracting the two safety devices 911 and 922 when the door 941 is opened and at the same time to lock the manual tripping mechanism so that the machine cannot be operated with a possible wastage of postage when the door is open. This automatic means includes a push rod 953 (Figures 2, 4 and 5) slidably extending through front plate bearing 954 and meter supporting bracket bearing 955. The push rod may be offset at 956 as shown in Figs. 4 and 5 to clear the tape magazine and other parts of the machine. The forward end of push rod abuts against the rear face of door 941 so that when the door is closed, the end of the rod will be maintained in its retracted position (Fig. 4), and when the door is opened to project forwardly as shown in Fig. 5. The rear end of push rod 953 engages a horizontally extending arm 957 projecting from the lower end of shaft 958 which shaft is journaled in brackets 959 and 960 securely fastened to the rear face of meter bracket 162 as by means of screws 961 (Figs. 4 and 5). To maintain shaft 958 in vertical alignment in bearings 959 and 960, a cotter pin 962 extends through the shaft just above bearing 959 and a thrust washer 963 is interposed between the cotter pin and upper surface of the bearing. The upper end of shaft 958 is provided with a horizontally extending arm 964 which when the door 941 is in its closed position as shown in Fig. 4, extends in front of the stop lever 918 and stop arm 928 of the two safety devices 911 and 922. As will be noted in this figure, sufficient space is left between the stop levers and shaft arm 964 to permit the stop levers to function in the manner previously described. However, when the door is open as shown in Fig. 5, the shaft arm 964 will engage and swing the stop lever 918 and stop arm 928 rearwardly. This action will position stop arm 928 directly above the short lug 937 of control lever 929, thereby locking the control lever against clockwise rotation as viewed in this figure and in this way, as previously described, will lock the manual tripping lever so that the machine cannot be placed in operation. Swinging of the control lever 918 and control arm 928 rearwardly serves to withdraw the feeler finger 912 of the first safety device clear of the path of travel of the

5 tape through the horizontal portion 718 of the tape guide chute 713 and to lift the offset portion 925 of bellcrank lever 932 of the second safety device 922 clear of the anvil and its groove 927. The retraction of the two safety devices is for the purpose of facilitating threading of the tape into the tape guide chute 713 in the manner previously described.

10 A tension spring 965 (Figs. 4 and 5) is interposed between the horizontal arm 957 and meter bracket 162. As arm 957 is relatively close to the rear face of bracket 162, it is preferable to extend the tension spring through a suitable opening formed through this bracket and to secure the inner end of spring 965 to the forward face of this bracket by means of spring pin 966. The tension spring 965 yieldingly acts to maintain arm 957 in engagement with the rear end of push rod 953. When the door is opened to release the push rod 953 the tension spring will act to 15 retract the two safety devices in the manner described. The return of the door to its closed position will act to positively rotate shaft 958 and to thereby return the shaft arm 964 to its inoperative position as shown in Fig. 4. The operation of the safety devices upon opening or 20 closing of the door is simple and effective and not only prevents accidental operation of the machine which may cause a waste of postage, but also facilitates threading of the tape into the tape 25 guide chute 713. This constitutes one of the important features of the machine.

30 It will be understood that the tape feeding device need be only threaded when a new roll of tape is mounted therein and that it may be moved freely from its non-printing to its printing positions and vice versa without disturbing the position of the tape within guide chute 713.

35 It will accordingly appear that our tape feeding device described above attains the several 40 objects noted herein in a thoroughly practical and efficient manner.

45 As many possible embodiments may be made of the above invention and as many changes might be made in the embodiment above set forth, it is to be understood that all matter hereinbefore set forth or shown in the accompanying drawings is to be interpreted as illustrative and not in a limiting sense.

50 We claim:

1. In a tape printing machine having a printing head, means for guiding tape from its supply to printing register wherein the free end of the tape is located adjacent said head, a detecting means located to engage the tape adjacent its free end at the exit end of said tape guiding means when the tape is in proper printing register, and means operatively responsive to said detecting means for rendering the machine inoperative when the end of said tape is not in position to be engaged by said detecting means.
2. In a tape printing machine, a magazine from which a supply of tape is withdrawn, a casting enclosing said magazine and having a suitable opening, a closure for said opening, means for guiding tape from said magazine to printing register, a detecting means located to engage the tape adjacent its free end when the tape is in proper printing register, and operative for rendering the machine inoperative when the end of said tape does not engage said detecting means, and means actuated by the opening of said closure for retracting said detecting means to facilitate threading of the tape into said guide means.

3. In a tape printing machine, a magazine from which a supply of tape is drawn, a casing enclosing said magazine and having a suitable opening, a closure for said opening, means for guiding tape from said magazine to printing register, a detecting means located to engage the tape adjacent its free end when the tape is in proper printing register, and operative for rendering the machine inoperative when the end of said tape does not engage said detecting means, and means actuated by the opening of said closure for rendering the machine inoperative, and for retracting said detecting means.

4. In a tape printing machine, a magazine from which a supply of tape is drawn, a casing enclosing said magazine and having a suitable opening, a closure for said opening, means for guiding the tape from said magazine to printing register, a detecting means located to engage the tape at a locality spaced from the leading end of said tape a distance equal to or greater than the length of tape necessary for one or more printing operations, said detecting means being operative for rendering the machine inoperative when the trailing edge of the tape passes from under said means, and means actuated by the opening of said closure for retracting said detecting means to facilitate threading of the tape into said guide means.

5. In a tape printing machine, a magazine from which a supply of tape is drawn, a casing enclosing said magazine and having a suitable opening, a closure for said opening, means for guiding the tape from said magazine to printing register, a detecting means arranged to engage the tape at a locality spaced from the leading end of said tape a distance equal to or greater than the length of tape necessary for one or more printing operations, said detecting means being operative for rendering the machine inoperative when the trailing edge of the tape passes beyond said means, and means actuated by the opening of said closure for rendering the machine inoperative and for retracting said detecting means.

6. In a tape printing machine, in combination, a printing head, a magazine from which a supply of tape is withdrawn, a casing enclosing said magazine, means in said casing defining a tape chute for guiding the tape from the supply to a printing register position adjacent said printing head, and detecting members located at the entrance and exit of said chute on opposite sides of said printing head for engaging the tape when the tape is in proper printing register, said detector members being operative for rendering the machine inoperative when said tape does not engage said members.

7. In a tape printing machine, in combination, a printing head, a magazine from which a supply of tape is withdrawn, means in said casing defining a tape chute for guiding the tape from the supply to a printing register position adjacent said printing head, detecting members located at the entrance and exit of said chute on opposite sides of said printing head for engaging the tape when the tape is in proper printing register, said detector members being operative for rendering the machine inoperative when said tape does not engage said members, and means for retracting said members to facilitate threading of the tape into said chute.

8. In a tape printing machine having a printing head, in combination, a magazine from which a supply of tape is withdrawn, means for guiding tape from said magazine to printing register

10

wherein the free end of the tape is located under said printing head in a position to receive an impression therefrom, manually operable means for actuating said machine to print on said tape, and detecting means adjacent said tape guiding means and adapted to engage the tape when the tape is in said proper printing register and operative to preclude operation of said manually operable means when said tape does not engage said detecting means.

9. In a tape printing machine, in combination, a rotatable platen, a rotatable printing head, means including a clutch for rotating said platen and head, means for guiding tape to printing register between said platen and head, detecting means located on opposite sides of the nip between said printing head and platen to engage the tape when the tape is in proper printing register, means for effecting actuation of said clutch to cause rotation of said head and platen, and interlock means and said clutch associated with said detecting means and effective when said tape does not engage said detecting means to prevent operation of said clutch actuating means.

10. In a tape printing machine, in combination, a printing member, means defining a tape chute for guiding the tape to a printing position adjacent said printing member, said chute having openings formed therein adjacent its entrance and exit ends and on opposite sides of said printing member, detector fingers located at said entrance and exit ends of the chute and extending through said openings respectively for engaging the tape when the tape is in proper printing position, and means responsive to said fingers when said tape does not engage both for rendering the machine inoperative.

11. Apparatus according to claim 10 in which the operating mechanism of the machine includes a clutch and clutch actuating means, and means forming an interlock between said fingers and said clutch actuating means for preventing operation of said clutch actuating means when the tape is not engaged by both of said fingers.

12. Apparatus according to claim 6 wherein the entrance and exit ends of said chute are connected by a curved portion, and said detecting members comprise fingers pivotally mounted on said tape chute defining means.

13. In a tape printing machine, in combination, a rotatable platen, a rotatable printing head, tape guiding and supporting means, means mounting said supporting and guiding means for bodily movement into and out of operative position relative to said platen and head, said guiding and supporting means having tape entrance and exit ends, and detecting members mounted on said guiding and supporting means so as to be movable therewith and located at said entrance and exit ends for engaging the tape when the tape is in proper printing register relative to said platen and head and said detecting members being operative for preventing rotation of said platen and head when said tape does not engage said members.

14. In a machine for printing a postage value on a strip of tape, the combination of, a platen, a printing head, tape guiding and supporting means, said guiding and supporting means being of a length in excess of the length of the printed matter impressed on the tape by the printing head, and detector means associated with the said guiding and supporting means and located

on opposite sides of the nip between the platen and printing heads for preventing operation of the printing head when the length of tape in the guiding and supporting means is insufficient to receive a full impression from the printing head. 5

15. In a machine for printing a postage value on a strip of tape, the combination of, a platen, a printing head, tape guiding and supporting means, said guiding and supporting means being of a length in excess of the length of the printed matter impressed on the tape by the printing head, and detector means associated with the entrance and exit ends of said tape guiding and supporting means and being located on opposite sides of the nip between the platen and printing head for preventing operation of the printing head when the length of tape in the guiding and supporting means is insufficient to receive a full impression from the printing head. 15

Certificate of Correction

Patent No. 2,415,762.

February 11, 1947.

COMMODORE D. RYAN ET AL.

It is hereby certified that errors appear in the printed specification of the above numbered patent requiring correction as follows: Column 3, line 17, for the reference numeral "810" read *710*; column 5, line 66, for "832" read *932*; column 10, line 21, claim 9, strike out the words "and said clutch" and insert the same after "detecting means", line 22, same claim; and that the said Letters Patent should be read with these corrections therein that the same may conform to the record of the case in the Patent Office.

Signed and sealed this 2nd day of September, A. D. 1947.

[SEAL]

LESLIE FRAZER,
First Assistant Commissioner of Patents.
